REFLUX DISTRIBUTOR FOR GAS LIQUID
CONTACT APPARATUS

Carolus S. Woodwell, Buffalo, N. Y., assignor to
National Aniline & Chemical Company, Inc.,
New York, N. Y., a corporation of New York

Application February 27, 1937, Serial No. 128,143

8 Claims. (Cl. 261—111)

The present invention relates to gas liquid contact apparatus, and particularly to a device for feeding reflux or scrubbing liquid to a fractionating or absorption column, respectively, of the packed tube type.

In distillation and absorption processes using a multiple tube packed column, it is advantageous to most efficient operation to return reflux condensate to the tubes of the still constantly and in uniform predetermined ratio to the various tubes throughout the period of distillation.

An object of the present invention, accordingly, is to provide means for effecting constant return of condensate in uniform predetermined ratio to the tubes of the still.

Further objects and advantages will be apparent from a consideration of the following description taken in connection with the accompanying drawing, wherein

Fig. 1 is a vertical section through a fractionating column embodying the invention, parts related therewith being shown diagrammatically; and

Fig. 2 is a horizontal section taken on the line II—II of Fig. 1.

The fractionating column 1 is secured at its lower end by a flange 2 to the upper end of a still 3, a portion of which is broken away in the drawing. A pipe 4 is communicably connected with the upper end of column 1 to conduct the vapor distillate to condenser 5. The condensate outlet from the condenser 5 is connected with a flow box 6 from which a portion of the condensate returns through the pipe 7 to the fractionating column and the remainder of the condensate is carried to the receiver 8 which is connected with the flow box 6 by a pipe 9.

In general, the fractionating column 1 is composed of a packed tube section 10 and a reflux distributing section 11, both of which are contained within a large diameter pipe 12. Near the lower end of pipe 12 is a tube plate 14 secured about its periphery to the pipe. Within openings of the tube plate 14 are secured the lower ends of a multitude of spaced tubes 15, the diameter of which preferably does not exceed three inches. The tubes 15 are filled to a height at least 25 times the diameter of the tubes with conventional packing material 16 which suitably may be Raschig rings. The amount of packing material in the tubes is so adjusted that each tube offers substantially the same resistance to fluid flow therethrough. The packing material in the tubes is supported by conventional means as, for example, a tapered spiral 17 of wire or a slotted cap

attached to the lower end of each tube. Spaced from the upper end of the pipe 12 is a second tube plate 18 which is also secured about its periphery to the pipe. The upper ends of the tubes 15 are secured in openings in the plate 18. The upper surface of the tube plate 18, as more clearly indicated in Fig. 2, is divided into a plurality of sectorial compartments within each of which is the upper end of one of the tubes 15. The division is effected by means of uniformly spaced upwardly extending radial baffles 31 which are affixed at one end thereof to the inner cylindrical surface of the reflux distributing section 11 and at the other end are joined at the center of the tube plate 18 (or are supported by means of a cylindrical ring—not shown in the drawing—at the center of the tube plate 18).

A sprayer 19 which is adapted to be rotated at high speed is provided to distribute reflux distillate returning through the pipe 7 which enters the head 11 of the column above the tube plate 18. The upper end of pipe 12 is closed with a cover 20 which is secured to a flange 21 about the end of the pipe. Eccentrically placed in the cover is a sight glass 22 through which the distributing action within the pipe may be observed. Centrally placed in the cover is a bearing 23 within the upper end of which is packing material held in place by packing nut 24. Shaft 25 carried by the bearing 23 is supported at its upper end by bearing 26 rigidly supported from the cover 20 by means of arms 27. To retain shaft 25 in proper vertical adjustment, safety collars 28 are provided thereon both above and below the bearing 26. Keyed to the upper end of shaft 25 is a drive pulley 29, driven from any suitable source of power. Secured to the lower end of the shaft is a horizontally rotating conical sprayhead 30 forming a cup into which the return pipe 7 delivers the returned distillate. The sprayhead may be in the form of a flat plate or solid cone instead of the cup or inverted cone shown in the drawing. In operation the particles of liquid discharged from the rapidly rotating sprayhead 30 will impinge against the inner cylindrical surface of the column head 11 at points above the edges of baffle members 31. As sprayhead 30 delivers an equal quantity of distillate in all directions the quantity delivered to each compartment and hence to each tube is equal.

In the embodiment of the invention shown, the top of tube plate 18 is divided into five equal compartments for dividing the reflux uniformly into five equal portions. If it is desired to feed reflux

or scrubbing liquid uniformly in predetermined unequal portions to the packed tubes, the radial baffles are so disposed that the angles therebetween are proportional to the desired divisions of liquid.

5 The chamber in the tube section 10 between the tubes 15 may contain air which dissipates the heat, or, if desired, it may be equipped with a suitable inlet 32 and outlet 33 for circulating any 10 fluid in heat exchange relation with the tubes 15, if such is desirable for the particular material being fractionated, or it may be filled with a suitable packing material, for example, infusorial earth, glass, wool asbestos, to decrease radiation.

15 In operation, material is introduced into still 3 in any suitable manner and is heated to drive vapors upwardly into the fractionating column 1. The system may be run under reduced pressure applied to the receiver if desired. Vapors 20 rising in the column 1 enter the tubes 15 where they are fractionated by their passage counter-current to the reflux. The vapors after partial condensation due to fractionation enter the column head 11 which they leave by way of the pipe

25 4, by which they are conducted to the condenser 5. The condensate therefrom is delivered to the flow box 6 from which a portion is returned to the head 11 and the remainder is delivered to the receiver 8. The portion of the condensate admitted to column head 11 by means of pipe 7 is allowed to flow continuously upon the upper surface of the revolving cup 30, the centrifugal force exerted by the rotating cup causing discharge of the liquid in the form of a sub- 30 stantially continuous liquid sheet or curtain of spray. The discharged condensate strikes the inner cylindrical surface of the column head 11 and is evenly distributed thereover. It then

35 flows downwardly, and the edges of the baffle 40 members 31 effect a subdivision of the liquid into a plurality of equal portions each of which collects in an appropriate sectional compartment formed by adjacent baffle members. The liquid portion thus collected in each compartment flows 45 into the tube opening located therein. As the tubes are of equal diameter and are so packed that they offer substantially equal resistance to fluid flow, and the reflux to each tube is equal, the fractionation obtained in the various tubes 50 is equal, thereby maintaining the efficiency of the unit. Thus, a unit containing a multiplicity of tubes three inches or less in diameter, packed to a height of eight feet with $\frac{1}{2}$ or $\frac{1}{4}$ inch Raschig rings, has an efficiency equal that of a thirty to thirty-five plate column of the bubble 55 cap type.

In the preferred embodiment of the invention disclosed, the various tubes are of equal diameter and the baffles 31 are equally spaced. However, 60 the invention is not limited thereto but includes the use of tubes of different sizes in conjunction with radial baffles spaced according to the cross sectional area of the tubes. In either case the liquid is uniformly distributed to the tubes in 65 the ratio set by the spacing of the radial baffles. Moreover, if desired, the baffles may be spaced to distribute the liquid uniformly in either equal or unequal predetermined portions regardless of the sizes of the tubes to which the portions 70 of liquid are delivered.

While the apparatus of the present invention in a preferred aspect is adapted to use in a process of fractionation, in its broader aspect it is adapted to use in processes generally wherein 75 efficient contact of liquid and gas is desired. For

example, in gas absorbing and scrubbing towers the gas inlet would be at the bottom of pipe 1, and the wash fluid would be delivered to the upper ends of tubes 15 by the pipe 7 and sprayer 19.

It should be understood that the term "gas" as used in the appended claims refers to the physical state, regardless of whether or not the gas is condensable to a liquid at the operating temperature by pressure alone.

As various changes may be made in the specific 10 embodiment without departing from the invention, it will be understood that the invention is not limited thereto.

I claim:

1. A fractionating column of the packed tube 15 type, comprising a multiplicity of vertical tubes, a header plate into which said tubes extend, means on said header plate forming a plurality of compartments with each of which the upper end of one of said tubes communicates said column having an outlet located above said compartments for removal of fractionated vapors from said column, and means for introducing and distributing liquid among said compartments. 20

2. A gas-liquid contact column comprising a multiplicity of tubes of equal cross-sectional area, means for introducing a gas into the lower ends of said tubes, means joining the upper ends of the tubes into a head, a plurality of compartments in said head with each of which one of said tubes communicates, said column having an outlet located above said compartments for removal of said gas from said column, means for introducing a stream of liquid into 30 said head and means in said head to distribute the said stream of liquid uniformly among said compartments. 35

3. A fractionating column of the packed tube 40 type, comprising a multiplicity of vertical tubes of equal cross-sectional area, means joining the upper ends of said tubes into a head, baffles dividing the upper surface of said means into a plurality of compartments in each of which one of said tubes terminates, said column having an 45 outlet located above said baffles for removal of fractionated vapors, means for introducing reflux into said head and a sprayer for distributing said reflux uniformly among said compartments.

4. A fractionating column of the packed tube 50 type, comprising a multiplicity of vertical tubes, means joining the upper ends of said tubes into a head, radial baffles dividing the upper surface of said means into a plurality of radial compartments in each of which one of said tubes 55 terminates, said column having an outlet located above said baffles for removal of fractionated vapors, means for introducing reflux into said head and a horizontally rotating spraying disc upon which the introduced reflux is delivered for distributing said reflux uniformly among said compartments. 60

5. A fractionating column of the packed tube type, comprising a multiplicity of vertical tubes, a tube sheet joining the upper ends of said tubes 65 into a head, radial baffles dividing the upper surface of said tube sheet into a plurality of radial compartments in each of which one of said tubes terminates, said column having an outlet located above said baffles for removal of fractionated vapors, means for introducing reflux into said head and a horizontally rotating sprayer for distributing said reflux uniformly among said compartments. 70

6. A fractionating column comprising a multi-

plicity of packed spaced tubes joined at their respective ends by tube plates, means for delivering vaporous distillate to the lower ends of said tubes, an opening in said column above the upper end of said tube plates through which vaporous distillate may leave said column, and means for distributing a portion of said distillate which leaves said column after having been condensed uniformly in equal portions among said tubes, 10 said means comprising upstanding radial baffles dividing said upper tube plate into a plurality of equal radial compartments in each of which one of said tubes terminates, and a horizontally rotatable sprayer onto which said portion of distillate is delivered whereby it is distributed 15 equally among said compartments and hence among said tubes.

7. In a fractionating system of the type having a fractionating column and means for condensing distillate removed from the column and returning a portion of the condensed distillate to the column, a fractionating column of the packed tube type, comprising a multiplicity of tubes spaced from each other and having packing material therein, means for introducing vapors into the lower ends of said tubes, means joining the upper ends of the tubes into a head, means to withdraw fractionated vapors from said head, baffles on said means joining the upper

ends forming a plurality of compartments within each of which one of said tubes terminates, and means in said head to distribute the returned portion of condensate uniformly among said compartments.

8. A fractionating column comprising in combination a vertical hollow shell, vertically spaced tube plates located within said shell, a plurality of spaced vertical packed tubes extending between and secured to said tube plates, all of said tubes being of uniform cross sectional area, said tube plates and shell defining a header located above said upper tube plate and a header located below the lower tube plate, said first named header having an outlet for removal of gas from said column, means within said first named header forming a plurality of compartments with each of which the upper end of one of said packed tubes communicates, means for introducing liquid into said upper header, a horizontally rotatable sprayer for continuously distributing liquid among said compartments, said compartments being of substantially uniform size whereby said liquid is substantially uniformly distributed simultaneously into all of said packed tubes, and means for introducing vapors to be fractionated into said lower header.
